United States Patent

Des. 235,172

Patented May 20, 1975

235,172

CATHETER

Jack L. Boone, Larkin Township, Midland County, Mich.,
assignor to Dow Corning Corporation, Midland, Mich.

Filed Mar. 12, 1973, Ser. No. 340,487

Term of patent 14 years

Int. Cl. D24—04

U.S. Cl. D83—12 A

Fig. 1

FIG. 1 is a perspective view of a catheter illustrating my new design; and

FIG. 2 is an elevation as seen from the opposite side of FIG. 1, with portions broken away for ease of illustration.

I claim:

The ornamental design for a catheter, as shown and described.
